(57) **CLAIM**

The ornamental design for an outdoor luminaire, as shown and described.

DESCRIPTION

FIG. 1. is a front view of the outdoor luminaire illustrating the new design;

FIG. 2. is a top view thereof;

FIG. 3. is a bottom view thereof;

FIG. 4. is a left side view thereof; and,

FIG. 5. is a right side view thereof.

The broken lines shown on the drawings are for illustrative purposes only and form no part of the claimed design.
